UNITED STATES PATENT OFFICE.

SALVATORE DANIELLI, OF MILAN, ITALY.

DRESS FASTENING.

Application filed March 31, 1928, Serial No. 266,382, and in Italy April 7, 1927.

This invention relates to improvements in dress fastenings and is concerned with grip fastenings adapted for use with suspenders, garters, braces, sleeves, petticoats, bands and the like.

One object of this invention is to provide a fastening of the character referred to which is adapted for taking an instantaneous grip on fabric when applied thereto in a very simple manner.

Another object is to enable the fastening device to be applied and engaged with the fabric by the aid merely of two fingers of one and the same hand in contrast with fastenings of the kind usually adopted and which require the employment of two hands for their application and engagement with or attachment to the fabric.

A further object of the invention is to produce a fastening of the character referred to from a single piece of sheet material and by means of simple stamping and bending processes.

A further object of the invention is to adapt the parts so that the formation of one part protects the wearer against the gripping means on the other part.

According to this invention the fastening device consists of a disc of metal, celluloid or other suitable material, the said disc being provided with projecting parts which are folded back upon the disc, one of said parts being adapted for the attachment of suspensory means and the other or others being formed or fitted with fabric gripping means.

The said parts when folded are bent to a curvature or convexity whereby the gripping means on the one part are outstanding sufficiently for engaging with the fabric to be gripped but are prevented from injuring the skin of the wearer by the curved projection provided by the bending of the other part.

The novel features just referred to, and other features, will be fully described by the aid of drawings accompanying this specification and illustrating one suitable example of construction, in which drawings:—

Figure 1 is a plan to a somewhat enlarged scale of a blank which may be produced by stamping and which is adapted for the production of a fastening device in one piece.

Figure 2 is a rear elevation of a fastening device produced from the blank in Figure 1, the said device being engaged with a suspensory cord or the like.

Figure 3 is a front elevation of Figure 2.

Figure 4 is an edge view of the fastening device seen in Figures 2 and 3.

Figure 5 is a side view of Figure 2 but with the fastening device engaged with a piece of fabric which may be that of a stocking.

Figure 6 is an elevation but to a smaller scale than the preceding figures and showing the fastening device partly applied to a garter.

Figure 7 shows the device when fully applied to the garter and attached to a stocking or the like.

Referring to Figures 1 to 5 of the drawings, 1 is a disc of metal, celluloid or other suitable sheet material, this disc being formed at diametrically opposite points with projecting parts 2 and 5. In this example, the projecting part 2 is rounded so as to be more or less of disc formation whereas the projecting part 5 has the form of a strip with parallel sides. However, these parts may have other suitable formations and there may be more than one part such as 2 in which case the parts 2 could not be diametrically opposite the part 5. The part 2 is formed with a slot which may have the half-moon formation shown, and from the straight edge 4 of this slot there project inwardly thereof two triangular points 3. These are the gripping points and more than two may be provided if desired. As will be apparent, a blank having the features just described may be produced by stamping. The blank may be perforated at 10 at the point where the part 5 joins the periphery of the disc 1.

The construction of the fastening is completed by folding the parts 2 and 5 back upon the disc 1 about folding lines just outside the periphery of the disc 1. In such folding, the parts 2 and 5 are bent, see Figures 4 and 5, so that they do not lie in a plane parallel with the plane of the disc 1 but are curved convexedly towards the rear. The points 3 which were downwardly directed in Figure 1 are now upwardly directed as seen in Figures 4 and 5, Figure 4 showing how the said points are outstanding sufficiently for being engaged with a piece of fabric, and such engagement being shown in Figure 5. The folded and bent part 5 serves for engaging the fastening device with a suspensory cord or the like 6 and, as will be apparent from Figure 5, the said part 5 projects with its curved surface to such an extent as to act as a guard and prevent the points 3 from inflicting any injury

upon the wearer when such points are presented towards the skin of the wearer.

The suspensory cord 6 may be an elastic ring, as shown in Figures 6 and 7, and suitable for suspension from clips 7 on a garter or like band 8 shown in dotted lines in these figures. The ring or cord 6 having been engaged with the two clips 7 after the garter 8 has been applied to the leg or arm, only the thumb and a finger of one hand are required to pull the fastening device down far enough to reach the top portion of a stocking 9. The fastening device is then merely pressed with its points 3 against the stocking, whereupon the said points make an instantaneous fastening which is very secure and non-injurious to the fabric. This is explained by the fact that when the acute angular points 3 enter the fabric they gradually open the texture or press the filaments apart but undue penetration of the points is avoided by the fabric coming against the straight edge 4 which acts as a stop, and provides a large resisting edge or surface for engaging the fabric. This formation of the points has been adopted after many trials and it has been found that tearing of the fabric does not take place and that after removal of the fastening there is little or no evidence that the fabric has been engaged with the points.

When the fastening device is to be released, it is only necessary to apply the thumb and finger to press the device downwardly a little, whereupon the points 3 are disengaged from the fabric and the fastening device is free.

It is to be understood, however, that the points 3 may be replaced by devices having pin-like points or other point formations, or by hooks or like grippers.

In the constructional example illustrated in the drawings, the fabric-gripping part 2 being disposed diametrically opposite the at-

tachment lug 5, it follows that the direction of pull must be perpendicular to the edge 4, as will be readily understood.

The perforation 10 may be used for the attachment of a suspensory cord or for other means of attachment.

I claim:—

1. Dress fastening comprising a disc 50 formed with integral peripheral projections, one of said projections being folded behind the disc and bent to a convexity and the other of said projections being formed with a slot having one straight edge with fabric gripping points projecting from such edge, said other projection being also folded behind said disc and bent to a convexity substantially as and for the purpose set forth.

2. Dress fastening comprising a disc 60 formed with integral projecting parts at diametrically opposite points, one of said parts being folded behind said disc and bent to form an attachment loop, and the other of said parts being formed with an opening 65 bounded along one side by a straight edge from which project pointed teeth, this part being also folded behind said disc in a manner similar to the first-named part substantially as and for the purpose set forth.

3. Dress fastening comprising a disc formed with integral projecting parts of diametrically opposite points, one projecting part of strip-like formation being folded back behind said disc and bent to present a rearward convexity, and the other projecting part of disc-like formation being formed with a half-moon opening and with teeth projecting from the straight edge of such opening, said other projecting part being folded back behind the disc and bent in a manner similar to the projecting part first-named substantially as and for the purposes set forth.

SALVATORE DANIELLI.
